UNITED STATES PATENT OFFICE.

SEWALL CABOT, OF BROOKLINE, MASSACHUSETTS, ASSIGNOR TO STONE TELEGRAPH AND TELEPHONE COMPANY, OF BOSTON, MASSACHUSETTS.

SIGNALING SYSTEM.

No. 899,240.

Specification of Letters Patent. Patented Sept. 22, 1908.

Application filed March 10, 1906. Serial No. 305,261.

To all whom it may concern:

Be it known that I, SEWALL CABOT, a citizen of the United States, and a resident of Brookline, in the county of Norfolk and State 5 of Massachusetts, have invented a new and useful Improvement in Signaling Systems, of which the following is a specification.

My invention relates to the art of transmitting intelligence from one station to another by means of electromagnetic waves, without the use of wires to guide the waves to their destination; and it relates more particularly to a complete system for transmitting and receiving such waves, which may be 15 operated by and in connection with existing wire telegraph systems.

The general object of my invention is to provide a wireless telegraph system which may be operated by and in connection with 20 existing wire telegraph systems without changing any of the operating features of such wire telegraph systems, but maintaining said operating features in their present form as in use today in the present state of development of commercial wire telegraph systems.

Another object of my invention is to provide a wireless telegraph transmitting system which may be operated by a wire telegraph transmitting operator located at a distance from said system; and a wireless telegraph receiving system, located at the same station as said transmitting system or at a different station, which may operate a sounder or other wire telegraph receiving apparatus located at a distance from said receiving system and which may be located at the same wire telegraph station as said transmitting operator.

Other special objects of my invention are 40 to provide wireless telegraph systems which may be operated by and in connection with existing wire telegraph systems and by which messages may be sent by front-stroke-Morse, so that said wireless telegraph systems may be operated by and in connection with existing open-circuit wire telegraph systems or existing duplex or quadruplex wire telegraph systems; and in general to employ wireless telegraphy to supplement such existing wire 45 telegraph systems in any and all possible ways, some of which are hereinafter set forth in the present application and others of which are set forth in my applications Serial Nos. 305,260, 305,262, and 305,263, filed simultaneously herewith.

Other objects of my invention will herein-after appear and will be particularly pointed out in the appended claims.

My invention may best be understood by having reference to the drawings which accompany and form a part of this specification and which diagrammatically illustrate organizations of apparatus and circuits whereby the hereinbefore stated objects may be realized.

In the drawings, Figure 1 is a diagram of a combined transmitting and receiving wireless telegraph system and an open circuit wire telegraph system so associated therewith that the wireless telegraph transmitting system may be operated by said wire telegraph system and said wire telegraph system may be operated by said wireless telegraph receiving system; Fig. 1^a is a schematic view of a signaling system comprising an open circuit wire telegraph system associated with a wireless telegraph system; Fig. 2 is a diagram of a combined transmitting and receiving wireless telegraph system associated in a similar manner with a duplex wire telegraph system; Fig. 2^a is a schematic view of a signaling system comprising a duplex wire telegraph system associated with a wireless telegraph system.

In the figures, V is an elevated conductor, 85 E is an earth connection, M is a transformer, I₁ and I₂ are transformer primaries and secondaries respectively, C is a condenser, L is an inductance, R is a resistance, K is a key, S is a spark-gap, A is an alternating current 90 generator or other suitable source of vibratory current, B is a battery, I is a wire telegraph line; and the various elements are distinguished from each other by the employment of exponents and subscripts.

As meant in this application, an open circuit wire telegraph system is one in which the sending keys normally are open, the relays normally are deenergized, their armatures being on their back contacts, and the sounder circuits normally are open, the sounder hammers being held up from their anvils against their up contacts. There may or may not be current normally on the line.

The open circuit wire telegraph system 105 shown in Fig. 1 is provided with a key K' which as shown is normally held by the spring f against its back contact 8 to which one terminal of the relay 11 is connected, the other terminal of said relay being shown as 110

earthed at E'' . The spring c normally holds the armature 12 against its back stop so that the sounder 14 normally is deenergized and the hammer 15 normally is held by the spring 6 d against its up contact. The key is connected to the line I which includes the armature 6 of the relay 5, the back contact 7 of said armature and the winding of the relay 2 which as shown is earthed at E' . It will be seen that the relays 11 and 2 normally are deenergized and that upon the depression of the key K' into contact with the front stop 9, the relay 11 remains deenergized and the relay 2 is connected in series with the battery B' . The resulting energization of the relay 2 causes the attraction of its armature 3 to its front stop 4 thereby closing the circuit of the magnet 1 through the battery B and energizing said magnet. The magnet 1 now causes the attraction of the key K thereby opening the circuit of the oscillation responder P at the point k'' , short-circuiting the receiving system between the points $o\ o'$ by the closure of contact k'' and grounding the transmitting system at the point E ; and finally closing the primary power circuit at k' . The generator A in said primary power circuit energizes the sonorous circuit $S\ C\ I_1$ and causes the radiation of electromagnetic waves from the elevated transmitting conductor system $V\ I_2\ s'\ o'\ E$. These waves will not differ appreciably from the simple harmonic form if the windings of the transformer M are so spatially related as to render the natural period of said sonorous circuit practically independent of the electromagnetic constants of said elevated conductor system. It will be noted that the operator at key K' sends front-stroke-Morse signals over the line I and that said signals are translated into front-stroke-Morse wireless signals by the transmitting wireless telegraph system and the apparatus associating it with the wire system. The electromagnetic signal waves so radiated are received at a distant station provided with the same apparatus as that shown in Fig. 1, and the resulting electrical oscillations developed in the elevated receiving conductor system $V\ I_2\ s'\ o'\ L''\ I_1'\ o'\ E$ are translated by the transformer M'' to the resonant receiving circuit $I_2''\ C_2''$ attuned to the frequency of said waves and preferably so related to the loop circuit $C_1''\ I_1''$ that its natural period is practically independent of the electromagnetic constants of said elevated receiving conductor system. The oscillation responder P, which in the present case is shown as consisting of a cell containing an electrolyte and having as its anode W 60 a wire about one mil in diameter inclosed in glass so that only its end is exposed, is operated by the difference of potential developed by said oscillations between the terminals of the condenser C_2'' and thereby causes the energization of the wireless telegraph relay Q, 65

the armature q of which closes the circuit of relay 5. The armature 6 of said relay is now drawn to its front contact 7' against the tension of the spring e and thereby closes the line I through the battery B'' , energizing the relay 11 and operating the sounder 14. 70

If a receiving operator fails to understand a signal or series of signals, he signals "break" by depressing the key K' and thereby transmitting electromagnetic signal waves 75 to the transmitting operator at the station from which signals are being transmitted; and the latter, receives the "break" signal, when his key K' is in its normal position, between his own signal elements. It will be noted that during transmission the difference of potential existing between the points o and o' , which form the terminals of the receiving system, is negligibly small and will not injure the delicate parts of said system. 80 It will be noted also that the point of connection of the receiving system to the transmitting system during transmission is a point having practically zero potential to ground so that the potential of the receiving system as a whole is not elevated during transmission as would be the case if said receiving system were connected during transmission to the transmitting system at a point other than one of zero potential. Although 85 the apparatus above described whereby a receiving operator may signal "break" without injuring the receiving apparatus is the form preferred by me in practice, I do not wish to be limited to this particular device 90 for "breaking", inasmuch as other arrangements may serve my purpose. 95

Although the line I has been described as a wire telegraph line, it will be obvious that it may consist of a conductor of a few feet in 100 length so that the key K' and its associated apparatus, including the receiving apparatus 11, 14 may be contained in the wireless telegraph station house. The advantage of the latter construction is that a transmitting operator cannot send wireless telegraph signals when a receiving operator at a distant station is "breaking", for when said receiving operator is "breaking" the conductor I is disconnected from the relay 2 by the attraction of the armature 6 to its front contact. 110 This advantage is an important one because the transmitting operator sometimes fails to receive a "break" signal when a telephone receiver is employed as the signal-indicating 115 device. 120

Fig. 1^a discloses schematically two terminal stations each comprising the apparatus and circuit arrangements shown in detail in Fig. 1. The reference characters in Fig. 1^a 12 indicate the same apparatus as the corresponding characters in Fig. 1 and subscripts and exponents are employed for differentiating such apparatus and circuit arrangements at the two terminal stations shown in Fig. 1^a. 13

R' represents the terminal station wire telegraph receiving apparatus and H' represents the apparatus which associates the wire telegraph system with the wireless telegraph system.

5 As is well understood by telegraphers, that particular type of open-circuit wire telegraph system known as the polar duplex system renders much better service especially over 10 long lines under unfavorable weather conditions than a simple Morse system. In Fig. 2 I have shown how a combined transmitting and receiving wireless telegraph system may be operatively associated with a duplex wire 15 telegraph system, the latter being employed not for sending two messages in opposite directions at the same time, but to obtain more efficient wire service as explained above. While I have shown in Fig. 2 a well known 20 form of polar bridge duplex, it is to be understood that I do not limit myself to such particular type of duplex system, inasmuch as any suitable type of duplex system such as the Stearns differential duplex or the polar 25 differential duplex or even a Stearns bridge duplex, may be substituted for said polar bridge duplex, and also a polar system, run according to the open-circuit system shown in Fig. 1, may be employed if desired.

30 The wireless telegraph features of the signaling system shown in Fig. 2 are identical with those shown in Fig. 1. In lieu of the armature 6 of the relay 5 of Fig. 1, I substitute in Fig. 2 an armature 6' carrying an extension provided with a double contact point 20 which in connection with the spring tongues 17, 18 and the fixed contact 19 constitutes a pole-changing key; and in lieu of the relay 2 of Fig. 1 I substitute in Fig. 2 a 40 polar relay 2' whose armature 3' is normally biased away from its front contact 4'. At the other end of the duplex system the key K' , by closing the circuit of the magnet 22 through the battery B' controls a similar 45 pole-changing key, and a polar relay 11' controls a sounder 14. 24 and 24' are the usual artificial lines employed for balancing the duplex system. The operation is as follows:—The operator at the terminal station 50 closes his key K' , thereby reversing the direction of the current from the battery B' , over the line and causing the relay 2' to close the circuit of the magnet 1 by the movement of the armature 3' over to the front contact 55 4'. The reversal of the current does not affect the relay 11' which is connected between the points $g' g'$ of the bridge arms R' , R'_1 , between which points no difference of potential is created by the current from the 60 battery B'_1 . The energization of the magnet 1 results in the transmission of electromagnetic waves in the manner explained above in connection with Fig. 1. The waves so transmitted are received at a distant receiving 65 station provided with the same apparatus

as that shown in Fig. 2 and operate the oscillation detector P . The operation of said oscillation detector results in the energization of the wireless telegraph relay Q and of the relay 5 which causes the pole-changing 70 key to reverse the direction of the current flowing from battery B'_1 over the line and thereby operates the relay 11' and sounder 14, without, however, operating the relay 2' or the transmitting magnet 1.

75 The operation of "breaking" is effected by depressing the key K' , and signaling "break" in the usual manner, and the electromagnetic waves thereby transmitted are received at the distant station between the signal elements of the message there being transmitted when the key K is in its normal position.

80 Fig. 2^a represents schematically two terminal stations each comprising the apparatus and circuit arrangements shown in detail in Fig. 2. The reference characters in Fig. 2^a indicate the same apparatus as the corresponding characters in Fig. 2 and subscripts and exponents are employed for differentiating such apparatus and circuit at the two terminal stations shown in Fig. 2^a. R'' represents the terminal station wire telegraph receiving apparatus and H'' represents the apparatus which associates the wire telegraph system with the wireless telegraph system.

85 I do not wish to be limited to the exact form of apparatus and circuit arrangements which I have herein shown and described for the purpose of more fully disclosing my invention, inasmuch as said apparatus and circuit arrangements are capable of a wide 90 range of variation without departing from the spirit of my invention.

95 I claim,—

1. In a signaling system, a wireless telegraph system and an open-circuit wire telegraph system operatively associated therewith.

100 2. In a signaling system, a wireless telegraph transmitting system, an open-circuit wire telegraph system, and means so associating said systems that said wireless telegraph transmitting system may be operated by said open-circuit wire telegraph system.

110 3. In a signaling system, a wireless telegraph receiving system, an open-circuit wire telegraph system and means so associating said systems that said open-circuit wire telegraph system may be operated by said wireless telegraph receiving system.

115 4. In a signaling system, a combined transmitting and receiving wireless telegraph system, an open-circuit wire telegraph system, and means so associating said systems that said wireless telegraph transmitting system may be operated by said open-circuit wire telegraph system and said wire telegraph system may be operated by said wireless telegraph receiving system.

120 5. In a signaling system, a combined

125

- transmitting and receiving wireless telegraph system including a sending device and an oscillation detector, an open-circuit wire telegraph system including a receiving apparatus, means controlled by said open-circuit wire telegraph system for operating said sending device, and means controlled by said oscillation detector for operating said receiving apparatus without operating said sending device.
6. In a signaling system, a wireless telegraph system including a sending device and a receiving device, an open-circuit wire telegraph system associated with said wireless telegraph system, and means operated by said receiving device for operating said wire telegraph system without operating said sending device.
7. In a signaling system, a wire telegraph system, means for sending front-stroke-Morse signals thereby, a wireless telegraph transmitting system, and means associated with said systems for converting said signals into front-stroke-Morse wireless signals, in combination with a wireless telegraph receiving system adapted to receive said wireless signals, a wire telegraph system, and means associated with said systems for converting said wireless signals into front-stroke-Morse wire signals.
8. In a signaling system, a wireless telegraph transmitting system, means for operating the same by an open-circuit wire telegraph system, a wireless telegraph receiving system and means for operating an open-circuit wire telegraph system thereby.
9. In a signaling system, a wireless telegraph transmitting system, means for operating the same by an open-circuit wire telegraph system, a wireless telegraph receiving system, means for operating an open-circuit wire telegraph system thereby, and means whereby the wire telegraph operators may "break" through the intermediary of said wireless telegraph systems.
10. In a signaling system, a combined transmitting and receiving wireless telegraph system including a sending device and an oscillation detector, an open-circuit wire telegraph system including a receiving apparatus, means controlled by said wire telegraph system for operating said sending device, and means controlled by said oscillation detector for closing said open-circuit wire telegraph system.
11. In a signaling system, a combined transmitting and receiving wireless telegraph system including a sending device and an oscillation detector, an open-circuit wire telegraph system including a receiving apparatus, a normally deenergized relay in said wire telegraph system operating said sending device only when said wire telegraph system is closed, and a relay controlled by said oscillation detector for operating said receiving apparatus without energizing said first mentioned relay.
12. In a signaling system, a wireless telegraph receiving system including an oscillation detector, an open-circuit wire telegraph line including a receiving apparatus and having the back contact and a mature of a relay connected thereto, a circuit controlled by said oscillation detector and including the winding of said relay, and means controlled by said relay for energizing said receiving apparatus.
13. In a signaling system, a wireless telegraph system and a duplex wire telegraph system operatively associated therewith.
14. In a signaling system, a wireless telegraph transmitting system, a duplex wire telegraph system, and means so associating said systems that said wireless telegraph transmitting system may be operated by said duplex wire telegraph system.
15. In a signaling system, a wireless telegraph receiving system, a duplex wire telegraph system and means so associating said systems that said duplex wire telegraph system may be operated by said wireless telegraph receiving system.
16. In a signaling system, a combined transmitting and receiving wireless telegraph system, a duplex wire telegraph system and means so associating said systems that said wireless telegraph transmitting system may be operated by said duplex wire telegraph system and said duplex wire telegraph system may be operated by said wireless telegraph receiving system.
17. In a signaling system, a wireless telegraph transmitting system, means for operating the same by a duplex wire telegraph system, a wireless telegraph receiving system and means for operating a duplex wire telegraph system thereby.
18. In a signaling system, a wireless telegraph transmitting system, means for operating the same by a duplex wire telegraph system, a wireless telegraph receiving system, means for operating a duplex wire telegraph system thereby, and means whereby the wire telegraph operators may "break" through the intermediary of said wireless telegraph systems.
19. In a signaling system, a combined transmitting and receiving wireless telegraph system, including a sending device and an oscillation detector, a wire telegraph system including a receiving apparatus, a polarized relay controlled by said wire telegraph system for operating said sending device, and a pole-changing key controlled by said oscillation detector for operating said receiving apparatus without operating said sending device.
20. In a signaling system, a wireless telegraph transmitting system including a sending key, a wireless telegraph receiving sys-

- tem including an oscillation detector, means operated by said key for rendering said oscillation detector inoperative, means for preventing the operation of said transmitting system when signals are being received by said receiving system and an open-circuit wire telegraph system operatively associated with said transmitting and receiving systems.
- 10 21. In a signaling system, a wireless telegraph transmitting system, a wire telegraph system comprising a normally deenergized line wire, means for applying a source of electromotive force to said line wire, and means so associating said systems that said wireless telegraph transmitting system may be operated by said wire telegraph system.
- 15 22. In a signaling system, a wireless telegraph transmitting system, a wire telegraph system comprising a line wire and a normally deenergized relay, means for energizing said relay and means controlled by said relay for operating said wireless telegraph transmitting system.
- 20 23. In a signaling system, a wireless telegraph transmitting system, a duplex wire telegraph system, a normally deenergized polarized relay and means controlled by said relay for operating said wireless telegraph transmitting system.
- 25 24. In a signaling system, a wireless telegraph transmitting system, a wire telegraph system, including a normally deenergized polarized relay, and means associating said systems whereby said relay will control the operation of said wireless telegraph transmitting system.
- 30 25. In a signaling system, a wireless telegraph receiving system, a wire telegraph system including a pole-changing key and means so associating said systems that said wire telegraph system may be controlled by the operation of said pole-changing key.
- 35 26. In a signaling system, a wireless telegraph receiving system, a wire telegraph system including a pole-changing key and means controlled by said key for translating the signals received by said wireless telegraph receiving system to said wire telegraph system.
- 40 27. In a signaling system, a wireless telegraph transmitting system including a sending key, a wireless telegraph receiving system including an oscillation detector, an open-circuit wire telegraph system so associated with said wireless telegraph transmitting and receiving systems that said wireless telegraph transmitting system will be operated by said wire telegraph system and said wire telegraph system will be operated by said wireless telegraph receiving system, means operated by said key for rendering said oscillation detector inoperative and means for preventing the operation of said transmitting system when signals are being received by said receiving system.
- 45 50 55 60 65

In testimony whereof, I have hereunto subscribed my name this 8th day of Mch. 1906.

SEWALL CABOT.
